SUPPORTING LEG ASSEMBLY FOR MARINE PLATFORM

George E. Suderow, New York, N.Y., assignor to De Long Corporation, New York, N.Y., a corporation of Delaware

Filed Sept. 28, 1956, Ser. No. 612,815

3 Claims. (Cl. 61—46.5)

This invention relates to convertible marine platforms and more particularly to supporting leg assemblies for such platforms having jacking means for relatively manipulating the supporting leg assemblies and platforms so that the latter can be converted from a floating platform to an elevated platform supported by the marine bottom above the water level and vice versa.

The present invention is particularly useful in the marine installation system such as disclosed in the Pointer application Serial No. 283,567, filed April 22, 1952, and now Patent Number 2,775,869. In general, this system embodies the utilization of a floating platform which may be transported to any suitable marine site, as by tugs or the like, and which is provided with a series of guide means for receiving a corresponding series of elongated supporting legs which are utilized when the floating barge has been transported to the marine site to support the floating barge from the marine bottom in an elevated position above the water level. The system disclosed in the aforesaid Pointer application illustrates the use of tubular one-piece supporting legs which are initially lowered through the platform guide means by means of pneumatically operated jacking mechanisms until the lower ends thereof are embedded in the marine bottom. Subsequently, the jacking mechanisms are operable to raise the platform on the supporting legs to a suitable height above the water level. With the platform thus supported, the same may be utilized for a variety of purposes. For example, permanent docks and piers have been constructed utilizing this system and it is also valuable in offshore drilling operations where the platform is to be used temporarily. In the latter case, the jacking mechanisms are operable to permit the platform to be lowered on the supporting legs until the same is again floating on the surface of the water and then to subsequently raise the supporting legs clear of the marine bottom and to a transporting position on the platform.

In most installations it is of importance to provide an elevated platform which has a substantially unobstructed upper deck surface. Due to the uncertainty and the unevenness of the marine bottom, it is usually the case when dealing with one-piece supporting legs that the upper ends thereof will project above the upper deck surface of the platform when the latter has reached its operative elevated position. In permanent installations the supporting legs can be welded or otherwise permanently secured to the platform and the upper ends cut off, but this is not practical in temporary installations. Moreover, this procedure is time consuming and costly.

Consequently, in a later application Serial No. 584,962, filed May 15, 1956, by George E. Suderow which is a continuation of application Serial No. 502,313, filed April 19, 1955, and now abandoned, it was proposed to construct the supporting legs of telescopic sections so as to insure that there would be no obstructing upper supporting leg ends extending above the platform deck when the same is elevated to its operative position. Moreover,

2

this sectional construction renders the legs easier to handle and affords more flexibility in operation.

Briefly, the telescopic supporting leg assembly disclosed in the above-mentioned Suderow application includes a plurality of telescoping sections having jacking mechanisms between adjacent sections with the outer section mounted for vertical movement with respect to the platform by a jacking mechanism carried by the platform. The jacking mechanisms disclosed by the platform. The jacking mechanisms disclosed are of the pin type embodying horizontally slidable pins engageable in a series of longitudinally spaced apertures formed in the supporting leg sections. While this type of jacking mechanism provides a positive mechanical restraint against movement of the sections, due to the fact that the pins must engage apertures which are spaced apart a fixed distance, there are inherent disadvantages in achieving minute incremental adjustments between the sections themselves and the sections with respect to the platform.

Accordingly, it is an object of the present invention to provide a telescopic supporting leg assembly of the type described having improved means for effecting relative longitudinal movement between the sections which readily enables minute incremental movements to be made.

Another object of the present invention is the provision of a supporting leg assembly of the type described having improved means for effecting longitudinal movement in either direction thereof with respect to a floating barge or platform even in minute increments.

Still another object of the present invention is the provision of a telescopic supporting leg assembly having improved means for selectively effecting or restraining relative longitudinal movement of the assembly with respect to a floating barge or platform and improved means for selectively effecting or restraining relative longitudinal movement between the sections of the assembly itself.

A still further object of the present invention is the provision of a supporting leg assembly of the type described which is simple in construction, easy to operate and economical to manufacture and maintain.

These and other objects will become more apparent during the course of the following detailed description and appended claims.

The invention may best be understood with reference to the accompanying drawings wherein an illustrative embodiment is shown.

In the drawings:

Figure 1 is a vertical sectional view showing a floating barge or platform having a telescopic supporting leg assembly embodying the principles of the present invention applied thereto and illustrating the same in a collapsed transport position;

Figure 2a is a view similar to Figure 1 illustrating the upper portion of the assembly in its extended operative position;

Figure 2b is a view similar to Figure 2a showing the lower portion of the assembly; and

Figure 3 is a cross-sectional view taken along the line 3—3 of Figure 1.

Referring now more particularly to the drawings, there is shown a telescopic supporting leg assembly, generally indicated at 10, which embodies the principles of the present invention. As was briefly noted above, the assembly of the present invention is particularly adapted to be utilized in the marine construction system disclosed in the aforesaid Pointer application, although it will be understood that the same may be readily used for other purposes. As shown, the assembly 10 is mounted on a floating barge or platform, indicated at 12. It will be understood that in accordance with the Pointer system, the floating platform 12 may be provided with a

series of telescopic supporting leg assemblies 10 which may be cooperatively operated so as to effect the various movements essential to the marine construction. In the drawings, only a portion of the floating platform is illustrated showing a single guide means 14 in the form of a vertical opening arranged to receive the single assembly 10.

The assembly 10 comprises a plurality of telescopically-arranged sections, generally indicated at 16, 18, and 20. It will be understood that any number of sections may be utilized, the three shown in the drawings being merely illustrative. The section 16 constitutes an outer section; the section 20, an inner section; and the section 18, an intermediate section. The exterior surface of outer section 16 is provided with a pair of diametrically opposed elongated racks 22 which extend longitudinally substantially throughout the entire length thereof. Each of the elongated racks is engaged by a worm gear 24 suitably journaled on the platform 12 for rotation about a vertical axis. Each worm 24 extends through the adjacent opening 14 into engagement with the cooperating rack 22 so as to effect or restrain relative longitudinal movement of the outer section with respect to the platform. Any suitable actuating means may be provided for driving each worm 24 and, as shown, a motor 26 is provided which turns a secondary worm gear 28 through a suitable reversing transmission 30. Each secondary worm gear drives a pinion 32 fixed with respect to the associated worm 24 so that rotation of the former will effect rotation of the latter. It will be understood that the motors 26 may be controlled in unison so that each worm 24 will be operated simultaneously so as to effect the vertical movement of the outer section.

A second pair of elongated racks 34 are mounted on the interior surface of the outer section in diametrically opposed relation and extend substantially throughout the entire length of the same. The upper end of the intermediate section has a pair of cooperating worms 36 mounted thereon for rotation about vertical axes. Each worm 36 is also provided with an actuating means including, as before, a reversible motor unit 38 driving a secondary worm gear 40 which in turn meshes with a pinion 42 mounted for movement with worm 36.

The intermediate section 18 is also provided with a pair of elongated racks 44 fixed to the interior surface of the section in diametrically opposed relation and extending substantially throughout the length of the same. Preferably, the racks 44 are displaced angularly with respect to the pair of worms 36 and, as shown, this angular displacement is approximately 90 degrees. The upper end of the inner section 20 has a pair of worms 46 mounted thereon for rotation about vertical axes and for cooperation with respective racks 44. As before, the worms 46 are provided with actuating means preferably in the form of a reversible motor unit 48 arranged to drive a secondary worm 50 which meshes with a pinion 52 mounted for rotation with the worm 46.

As best shown in Figure 3, the racks 22, 34 and 44 are formed with a concavely shaped exterior surface which engages a substantial portion of the periphery of the associated worm so as to prevent relative rotation between adjacent sections and between the outer section and the platform.

At the lower end of the inner section 20 there is mounted a telescopic footing assembly, generally indicated at 54. The assembly 54 preferably is constructed in accordance with the disclosure of copending application Serial No. 469,092, filed November 16, 1954, by George E. Suderow and now Patent No. 2,909,901. Briefly, the assembly 54 includes a plurality of inverted substantially cup-shaped members 56, 58, 60 and 62 of progressively diminishing diameter such that the same can be nested together in telescopic relation. Each of the members 56, 58, 60 and 62 includes a central aper-

ture through which the lower portion of the inner section 20 extends. The lowermost extremity of the inner section is provided with a radially outwardly extending peripheral flange 64 which is adapted to engage the lower inner periphery of the inner member 62. The inner member 62 is provided with an upper radially outwardly extending peripheral flange 66 which is adapted to engage a lower radially inwardly extending flange 68 on the adjacent member 60 so as to limit the relative movement between the two. Member 60 also includes an upper radially outwardly extending peripheral flange 70 which is adapted to engage a lower radially inwardly extending flange 72 on the member 58 so as to limit relative movement between the two. In a like manner, the member 58 includes an upper radially outwardly extending peripheral flange 74 which is adapted to engage a radially inwardly extending flange 76 on the lower end of the member 56 so as to limit relative movement between the two.

In utilizing the present invention in the system of the aforesaid Pointer application, it will be understood that a series of telescopic supporting leg assemblies will be utilized on a platform and simultaneously moved as described in that application. With the above in mind, operation of a single assembly of the present invention will now be described. After the floating platform or barge has been transported to a suitable marine site with the telescopic supporting leg assembly in its retracted leg position, as illustrated in Figure 1, the motors 26, 38 and 48 are actuated so as to set the corresponding worms 24, 36 and 46 into rotation. The precise order in which actuation of the motors 26, 38, and 48 is performed is of no particular significance, it being understood that they may be actuated simultaneously or alternately. The important consideration in actuating the various motors is to insure that when the supporting leg assembly has finally reached its operative position wherein the inner section is firmly embedded in the marine bottom and the outer section is carrying the platform at a suitable height above the water level, the upper end of the outer section will be maintained flush with the upper deck surface of the platform. It is this arrangement which makes the telescopic arrangement more advantageous than a one-piece supporting leg, such as described in the aforesaid Pointer application. Consequently, it will be readily appreciated that by suitably actuating one or more of the motors controlling the various worms, the above condition can be readily achieved.

It has been found preferable to actuate the inner member initially by operating the motor units 48, thus turning the worms 46. It will be understood that rotary movement of the worms 46 in one direction causes the inner section to move vertically downwardly with respect to the intermediate section due to the cooperation of the worms with the elongated racks 44. Of particular significance in this regard is that the worm and rack arrangement is of the self-locking type so that relative longitudinal movement between the inner section and intermediate section is restrained when motor units 48 are not in operation. Of course, this same restraining effect is present as between the worms 36 and racks 34 and the worms 24 and racks 22. This arrangement affords a positive lock between any two adjacent sections and at the same time permits minute incremental movement therebetween.

After the inner section has been lowered to its limiting extent within the intermediate section, the motors 38 of the latter are actuated to lower the intermediate section together with the inner section relative to the outer section. Here again, the operation of the worms on the racks 34 effects a highly advantageous movement. Generally, the marine bottom will be engaged during the lower movement of the intermediate and inner sections with respect to the outer section and this engagement continues until the bottom of the inner section and the telescopic footing assembly are firmly embedded in the marine bottom.

The footing assembly operates in the same manner as the aforesaid Suderow application Serial No. 469,092 and now Patent No. 2,909,901 and serves to afford greater support for the assembly 10 from the marine bottom when the latter is embedded therein.

With the telescopic supporting leg assembly embedded in the marine bottom, the motors are then actuated to rotate the worms 24 in engagement with the exterior legs 22 of the outer section. This operation effects a raising of the floating platform relative to the supporting leg assembly. When the platform has assumed a desired height above the water level, the upper end of the outer end section should be flush with the deck surface of the platform if suitable precautions have been previously undertaken. If this flush relationship does not exist, it is a simple matter to operate the motor units 38 of the intermediate section in conjunction with the motor units 26 of the platform so as to bring the upper end of the outer section into flush relation with the outer deck of the platform.

If the platform is used as a temporary installation, the above procedure may be reversed so as to again render the platform floating and permit the same to be transported to another site. It will be understood that the platform is first lowered on the supporting leg by reversing the direction of operation of the motor units 26 and 38 until the platform is again floating on the surface of the water. Next, the motor units are continued in reverse operation until the supporting leg is pulled free of the marine body utilizing the buoyant platform to resist the reaction force necessary to effect the freeing of the leg. Finally, the supporting leg is elevated to its transport position, shown in Figure 1, and the platform is ready for transport to a new site.

It can thus be seen that there is provided a telescopic supporting leg assembly which is particularly useful in a system such as described in the aforesaid Pointer application. The telescopic arrangement of the supporting leg serves to insure that for any given height to which the platform is ultimately raised, the upper end of the outer section may be brought into flush relation to the deck surface thereof. By providing a worm gear and rack arrangement for effecting relative movement between the platform and the assembly, as well as the relative longitudinal movement of the sections of the assembly itself, a positive locking by mechanical action is provided which insures that there will be no accidental relative movement as the result of power failure. Moreover, the arrangement is susceptible to minute incremental adjustments thus rendering the entire operation more flexible.

It thus will be seen that the objects of this invention have been fully and effectively accomplished. It will be realized, however, that the foregoing specific embodiment has been shown and described only for the purpose of illustrating the principles of this invention and is subject to extensive change without departure from such principles. Therefore, this invention includes all modifications encompassed within the spirit and scope of the following claims.

10 I claim:

1. In apparatus of the type described, the combination comprising: a platform, a vertically extending telescopic supporting leg including an outer section, an intermediate section, and an inner section, guide means on said platform mounting said outer section for substantially vertical movement in either direction relative to said platform, first vertically extending rack means fixed to the outer periphery of said outer section, first worm gear means carried by said platform operatively engaging said first rack means, first power means for driving said first worm gear means in either direction, second vertically extending rack means fixed to the inner periphery of said outer section, second worm gear means carried by the upper end of said intermediate section operatively engaging said second rack means, second power means for driving said second worm gear means in either direction, third vertically extending rack means fixed to the outer periphery of said intermediate section, third worm gear means carried by the upper end of said inner section operatively engaging said third rack means and third power means for driving said third worm gear means in either direction.

2. The combination as defined in claim 1 wherein said first, second and third rack means each comprises a pair of diametrically opposed elongated racks and wherein said first, second and third worm gear means each comprises a pair of worm gears operatively engaging an associated rack.

3. The combination as defined in claim 2 wherein said first, second and third power means each comprises a pair of pinion gears fixed with respect to the associated pair of worm gears and a pair of power transmission worm gears drivingly connected to said pinions.
